CHARLES J. B. GAUME, OF NEW YORK, N. Y.

Letters Patent No. 87,835, dated March 16, 1869.

IMPROVEMENT IN ELECTRO-MAGNETIC ENGINE.

The Schedule referred to in these Letters Patent and making part of the same.

To all whom it may concern:

Be it known that I, CHARLES J. B. GAUME, of the city, county, and State of New York, have invented a new and improved Electro-Magnetic Engine; and I do hereby declare that the following is a full, clear, and exact description thereof, which will enable others skilled in the art to make and use the same, reference being had to the accompanying drawings, forming part of this specification.

This invention relates to new and important improvements in electro-magnetic engines, whereby they are rendered more useful, as a "motor," than they have hitherto been; and

The invention consists in the construction and arrangement of parts, (but having more particular reference to an electro-magnetic engine invented by me, and for which Letters Patent of the United States, bearing date April 2, 1867, have been granted to me,) as will be hereinafter more fully described.

In the accompanying plates of drawings—

Figure 1 represents a front elevation.

Figure 2 is a side elevation.

Figure 3 is a back elevation.

Figure 4, a vertical section of the distributing-wheel and circuit-breaker, through the line $z z$, fig. 5.

Figure 5 is a vertical section of fig. 4, through the line $y y$.

Similar letters of reference indicate corresponding parts.

A represents the bed-plate of the machine.

B represents the frame, composed of two stands secured to the bed.

C is the shaft, which is supported by the frame B, in which it revolves.

D is the armature-wheel, which is firmly keyed to the middle of the shaft.

E represents the armatures, which are supported by the radiating arms, or spokes of the wheel D.

F represents the magnets, which are stationary, and radiate from hubs on the frame B, which project inward from the stands, and which hubs are marked G.

H is the distributing-wheel, which is placed loosely upon a bearing attached to the front stand of the frame.

I is the circuit-breaker, which is a disk-wheel, or roll, supported by an arm, J, which is attached to the shaft, and revolves with it.

In fig. 1, r represents three metallic bars, which receive and transmit the electricity from one to the other set of magnets.

The series of armatures E project in pairs from each side of the wheel, at equal distances from each other, as plainly seen in figs. 1 and 2.

The series of electro-magnets are arranged in pairs, six pairs on each side of the wheel being shown in the example of my invention, with eight pairs of armatures attached to the wheel.

These magnets have a radial position, as shown in fig. 1.

The wire by which these magnets are connected with the positive pole of the battery is connected at S, as shown in fig. 1.

The shaft works loosely through the fixed hubs G, to which the magnets are attached.

The distributing-wheel H is provided with insulated metallic rings $l l l$, the two former located upon opposite edges of the wheel, as shown in fig. 2, and the latter upon the outer face of the same, as shown in fig. 1.

$n n' n''$ represent a series of keys, insulated from each other, and connected, respectively, to the rings $l l l$.

The wire from the positive pole of the battery is connected with the post S, to conduct the current of electricity, through the spring-arm O, to the circuit-breaker I.

The operation is as follows:

Supposing the roll I to rest upon one of the keys, n' , at starting, the current passes to the ring l , and thence to the first magnet, through the wire t , on one side of the wheel D.

This magnet is connected to that directly opposite, and upon the same side of the wheel, by a wire, u .

The lower magnet, located in a similar manner upon the opposite side of the wheel, then receives the current, through the connecting-wires $v v'$ and one of the bars r , secured to the stand A, and connects the same, by the wire w , to that magnet which is in the same radial line.

By this arrangement, it will be seen that the two pairs of magnets will attract and move their corresponding armatures.

The wire X conducts the current from the last magnet to the battery, through the bar T and post S.

As soon as the armatures begin to move, the roll I will also move in a corresponding degree, breaking the circuit through the key n' and ring l , and passing to one of the keys, n'' , direct the current through the ring l' , and its corresponding magnets upon each side of the wheel.

This operation is continued, as the armatures are attracted and the wheel turned, to the keys n and ring l , and their corresponding magnets. The circuit, therefore, is broken and completed successively, as the roll I moves from one key to the other.

By this means, a continuous rotary movement is given the wheel D.

The arm J, which supports the circuit-breaker, or roll I, is a spring sufficiently flexible to press the roll to the wheel, and thereby keep it in contact with the keys at all times.

The wires from the two poles of the battery are connected with the engine by the two posts, or stands, marked $s s'$.

The motion and power of the engine is conveyed by a belt from the pulley T.

U represents a reversing-bar, attached to the distributing-wheel H, by which that wheel is moved or par-

tially rotated, so as to alter the relation between the keys and the magnets, and by which alteration the engine is made to run at different velocities, or rates of speed.

This is accomplished as follows: When the magnets and armatures are in the relative positions shown in fig. 1, and it is desired to move the wheel D to the right, the distributing-wheel H is moved, by means of the lever U, so as to direct the current through that set of magnets which are at the right of the armatures; and if it is desired to move the wheel D in the opposite direction, the distributing-wheel is shifted, so as to direct the current through the set of magnets, at the left of their armatures; and when it is desired to stop the rotation of the wheel D, the distributing-wheel H is so adjusted as to direct the current through each set of magnets, when the armatures are directly over, or are just leaving them.

The velocity with which the wheel is driven is reg-

ulated by the position of the armatures, with reference to the magnets, when the circuit is completed.

Having thus described my invention,

I claim as new, and desire to secure by Letters Patent—

The construction and arrangement of the stationary magnets, fixed upon the hub G, the revolving armatures secured to the balance-wheel D, parallel to the axis thereof, and the distributing-wheel H, loosely attached to the frame B, and made adjustable, for the purpose of regulating the speed and changing the direction of the revolving armatures, by means of wires connecting its insulated keys and rings with the several sets of magnets, in the manner herein shown and described.

CHARLES J. B. GAUME.
